CLAIM

The ornamental design for a combined bottle and cap, substantially as shown and described.

DESCRIPTION

FIG. 1 is a front elevational view of a combined bottle and cap showing my new design;

FIG. 2 is a side elevational view, the opposite side being the same in appearance;

FIG. 3 is a top plan view;

FIG. 4 is a bottom plan view;

FIG. 5 is a rear elevational view; and

FIG. 6 is a vertical sectional view taken through the center of FIG. 1.

Fig. 6.
